UNITED STATES PATENT OFFICE

152,871

DESIGN FOR A FOOD GRINDER

Milton C. Everett, Roosevelt, N. Y., assignor to
Stanley Wechsler, Nat Raskin, and Richard L.
Rossin, doing business as Stanat Tool and Ma-
chine Company, Long Island City, N. Y.

Application May 20, 1946, Serial No. 129,876

Term of patent 14 years

(Cl. D89—1)

To all whom it may concern:

Be it known that I, Milton C. Everett, a citizen of the United States, residing in Roosevelt, county of Nassau, State of New York, have invented a new, original, and ornamental Design for Food Grinder, of which the following is a specification, reference being had to the accompanying drawing, forming a part thereof, in which:

Fig. 1 is a top plan view of my new design for a food grinder;

Fig. 2 is a side elevational view thereof, looking from the left of Fig. 1;

Fig. 3 is a front elevational view thereof;

Fig. 4 is a side elevational view thereof looking from the right of Fig. 1, and

Fig. 5 is a bottom plan view thereof.

I claim:

The ornamental design for a food grinder, as shown.

MILTON C. EVERETT.
